UNITED STATES PATENT OFFICE.

AGNES DOUGLASS, OF PLATTEVILLE, WISCONSIN, ASSIGNOR TO WAITE CARPET COMPANY, OF OSHKOSH, WISCONSIN, A CORPORATION OF WISCONSIN.

DESIGN FOR A RUG.

Application filed June 11, 1928. Serial No. 27,073. Term of patent 7 years.

To all whom it may concern:

Be it known that I, AGNES DOUGLASS, a citizen of the United States, residing at Platteville, in the county of Grant and State of Wisconsin, have invented a new, original, and ornamental Design for Rugs, of which the following is a specification, reference being had to the accompanying drawing, forming part thereof.

The figure is a plan view of a rug showing my new design.

I claim:—

The ornamental design for a rug, as shown,
AGNES DOUGLASS.
